UNITED STATES PATENT OFFICE.

DANIEL M. WATSON, OF PORTLAND, OREGON.

PUMP.

1,313,359.

Specification of Letters Patent.

Patented Aug. 19, 1919.

Application filed February 19, 1917. Serial No. 149,524.

To all whom it may concern:

Be it known that I, DANIEL M. WATSON, a citizen of the United States, residing at Portland, in the county of Multnomah and State of Oregon, have invented certain new and useful Improvements in Pumps, of which the following is a specification.

This invention has reference to pumps and its object is to provide a pump in which no fluid passes through the working barrel, but is directed wholly about the working barrel.

The invention comprises a pump casing in which there is mounted a working barrel freely open at the opposite ends and there supported by spacing members lodged in the casing with one of the spacing members serving as a valve seat and having a valve structure associated therewith. The other spacing member is so constructed that the valve structure may be associated with it after being removed from the first spacing member, so that in the event of wear the working barrel may be reversed in position, thereby prolonging the life of the pump.

Associated with the working barrel is a pump plunger having packing means arranged for self packing and also arranged for taking up wear without the necessity of the removal of the plunger from the working barrel.

The invention will be best understood from a consideration of the following detailed description, taken in connection with the accompanying drawings forming part of this specification, with the further understanding that while the drawings show a practical form of the invention; the latter is not confined to any strict conformity with the showing of the drawings, but may be changed and modified so long as such changes and modifications come within the scope of the appended claims.

In the drawings:

Figure 1 is an elevation of the pump.

Figs. 2, 2^a and 2^b together show a longitudinal diametric section of the pump on a larger scale than Fig. 1.

Fig. 3 is a section on the line 3—3 of

Fig. 2.

Fig. 4 is a section on the line 4—4 of Fig. 2^a.

Fig. 5 is a section on the line 5—5 of Fig. 2^a.

Fig. 6 is a longitudinal section of a portion of a pump rod of tubular form.

Referring to the drawings there is shown a pump casing 1 of suitable length and diameter connected at the ends by couplings 2, 3, respectively, to respective reducers 4, 5. The reducer 4 is connected by a coupling 6 to a pipe 7 which may be assumed to lead to the top of the well for conducting the water or other liquid elevated by the pump. For convenience of description it will be considered that water is the liquid to be pumped. The reducer 5 is connected to a coupling 8 in which is lodged a check valve 9 and its seat 10, while another coupling 11 is connected to the coupling 8 by a nipple 12. The coupling 11 houses a check valve 13 with its seat 14, and connected to the coupling 11 is a strainer 15 which may be of ordinary construction and hence needs no special description. The two check valves 9 and 13 constitute foot valves, while the nipple 12 may be replaced by any appropriate length of pipe separating the two valves 9 and 13 to a greater extent than indicated in the drawings.

Within the coupling 3 there is lodged a spacer ring 16 interiorly threaded for the reception of one end of the working barrel 17 of considerably less diameter than the casing 1 and of greater length than the casing 1, so that one end 18 of the barrel 17 may extend through and beyond the ring 16 and the other end 19 of the working barrel may extend through and beyond another spacing ring 20 similar to the ring 16 and lodged in the coupling 2. The rings 16 and 20 are clamped between corresponding ends of the pump casing 1 and the respective reducers 5 and 4.

Screwed on to the threaded end 19 of the barrel 17 is a ball cage 21 confining ball valves 22 to the ring 20 in operative relation to passages 23 through the ring, the balls 22 seating at those ends of the passages 20 toward the case 21. Pockets 24 are formed in the cage 21 to receive the balls 22 and the ends of the pockets remote from those receiving the balls open through the cage by way of passages 25, so that the balls may move freely toward and from the passages 23 to close and open them. The cage 21 is small enough in diameter to have its peripheral portion spaced from the inner wall of the reducer 4, so that water passing through the valve structure has ample room to move about the cage into the reducer 4 above the cage. The ring 16 has

passages 26 therethrough corresponding to the passages 23, so that in the event of wear of the ring 20 the working barrel may be reversed in position and the cage 21 applied 5 to the end 18 of the working barrel confining the balls 22 to the ring to serve as valves for the passages 26.

Extending through, and in the showing of the drawings about as long as the working barrel 17, is a plunger 27 shown in Figs. 2 and 2^a as a solid plunger with an axially extended screw-threaded socket 28 in what constitutes its lower end in the working position. The end of the plunger 27 which in the 10 working position constitutes its upper end is provided with a screw-threaded neck 29 to which is applied a screw socket 30 at the lower end of a pump rod 31, which latter may be of the usual construction and needs 15 no special description.

Entering the threaded socket 28 at the lower end of the plunger is a threaded shank 32 of a screw 33 having a head 34 with a diametric recess 35 in the face remote from 20 the shank, the head being of a diameter to snugly yet freely fit the working barrel. Carried by the screw 33 between the head 34 and the lower end of the plunger is a series of packing rings 36 with a washer 37 25 interposed between the head 34 and the lowermost packing ring 36. That portion of the head 34 against which the washer 37 rests has passages 38 leading therethrough, so that water below the head 34 may have 30 free access to the washer 37, and under the pressure caused by pumping force the washer 37 against the packing rings 36. This results in the automatic compression of 35 the packing rings during the power stroke 40 of the plunger by the water being pumped acting against the packing rings through the washer 37.

When the plunger is first installed the screw 33 is screwed into the socket 28 to an 45 extent to compress the packing rings into sufficiently tight engagement with the working barrel to prevent leakage past them. In order that the compression of the packing rings by the screw may be varied as desired, 50 a pin or rivet 39 is placed in traversing relation to the reducer 5 immediately below the lower end of the working barrel and provided with a squared or other suitably shaped portion 40 in the path of the head 34 55 of the screw 33 when the plunger is lowered to a sufficient extent, the arrangement being such that the slot 35 will receive the squared portion 40 of the pin or rivet 39. Then, by turning the pump rod 31 the 60 plunger 27 may be similarly turned to cause the screw 34 to compress the packing rings 36 and so take up any wear which may have occurred. In this manner the packing 65 may be kept in a tight condition without the necessity of removing the plunger from the

well in which the pump is installed. Of course, continued wear will necessitate the ultimate removal of the plunger, but this need occur only at long intervals instead of the much shorter intervals necessitated by 70 wear in pumps as ordinarily constructed.

The pump works on the displacement principle with no water at all entering the working barrel except at the lower end on the upward movement of the plunger to be 75 discharged therefrom by the downward movement of the plunger. On the upward movement of the plunger water enters the pump casing after passing the check valves 13 and 9, and then on the downward movement of the plunger with the check valves closed the water is forced through the passages 26 into the pump casing 1. As the pump continues working the water rises 80 through the passages 23 and by the valve 85 members 22 and ultimately rises to the surface, the action of the pump in this respect being similar to ordinary pumps.

By making the plunger 27 with the packing at the lower end thereof longer than the working barrel, no water whatever enters the top of the working barrel and no additional work is placed upon the pump, as would be the case where water is forced to pass 90 through the working barrel with the consequent additional friction over the larger 95 passages provided by directing the water outside of the working barrel.

In deep wells a solid pump rod like the pump rod 31 is quite flexible. In order to 100 stiffen the rod it is made hollow, as shown at 31^a in Fig. 6. In place of the socket 30 used with a solid pump rod that end of the pump rod 31^a constituting its lower end in operation is provided with internal screw 105 threads 30^a to receive the screw-threaded neck 29 at the upper end of the pump plunger. The hollow rod 31^a is provided near its lower end with a perforation 41 and at an appropriate distance above the plunger 110 the hollow rod is closed by a plug 42 below which is a perforation 43 through the wall of the rod, the perforation 43 being quite close to the plug 42.

A hollow rod would necessarily have a 115 certain buoyancy. To overcome this the perforations 41 and 43 are spaced far enough apart to permit the flow of a sufficient quantity of water into the rod to counteract such buoyancy. In this way the rod is automatically made heavy enough to force the plunger downward without increasing the amount of metal in the pump rod, and materially stiffening the pump rod, since with 120 the same amount of metal the hollow rod is of considerably larger diameter than the solid rod. Such a hollow or pipe-like rod is in operation much stiffer than a solid rod of the same weight. By permitting a sufficient length of the hollow rod to fill with 125

water the weight of the rod is materially increased over that of a solid rod containing the same amount of metal.

When the plunger is lowered into the well 5 the hollow pump rod fills with water up to the plug 42 and when the plunger is pulled from the well, the contained water drains out through the perforation 41, the perforation 43 acting as a vent in either case.

10 The pump rod 31^a may be made of sections of suitable length joined together by couplings 44.

The pump is particularly useful in deep wells and especially for pumping oil where 15 sand or grit or silt is present. Under such conditions, when the pump is at rest, sand or the like, which is held in suspension in the oil, deposits upon the valves. In such deep well pumps, it is the custom to cause the 20 down stroke of the piston solely by gravity because of the impracticability of applying force to cause the down stroke to a pump rod many hundreds of feet in length. When the valves are located at or close to the lower 25 end of the pump barrel, a gravitating pump plunger lacks the necessary power to dislodge the sand, and therefore, if the deposit of sand be relatively heavy, the pump must be withdrawn from the well in order to clean 30 out the deposited sand. This is necessarily a time consuming and expensive procedure, and is not to be tolerated if it occurs frequently.

By extending the pump plunger above the 35 upper end of the working barrel to a distance which will maintain it always above the upper end of the working barrel, and by locating the valves close to the upper end of the working barrel, any deposits of sand 40 on the upper valves are subject to violent agitation due to the movements of the pump plunger. Consequently, a few strokes of the pump plunger dislodge all accumulated sand, thus avoiding any necessity of pulling 45 the pump for cleansing purposes.

What is claimed is:—

1. A pump comprising a pump casing, a working barrel within the pump casing, a displacement plunger for the working barrel, 50 rel, spacing means at the opposite ends of the working barrel for centralizing the latter in the pump casing, and valve members associated with one of the spacing means, said spacing means being of like construction for 55 the association of the valve means with either spacing member.

2. A pump comprising a casing, a working barrel freely open at the opposite ends with each end exteriorly screw threaded, a spacing ring at each end of the barrel threaded 60 thereon and provided with passages therethrough exterior to the barrel, a valve cage

and valve members applied to one end of the barrel in operative relation to the corresponding spacing ring and the passages 65 therethrough, and a displacement plunger for the working barrel.

3. A deep well pump comprising an upright casing, an open-ended working barrel within the casing, and a displacement plunger for the barrel having a stroke carrying its lower end below the working barrel, said plunger having packing at its lower end, and the casing below the barrel and the lower end of the plunger having co-operat- 70 ing means for taking up wear in the packing, comprising a screw on the lower end of the plunger and a fixed member extending transversely of the casing to engage the screw and actuate it by rotative movements 75 of the plunger.

4. A deep well pump comprising an upright casing, an open-ended working barrel within the casing, a reciprocatory displacement plunger located in the barrel and provided with packing at its lower end, a headed screw extending through the packing and a fixed member in the casing for engaging the head of the screw, said fixed member being located at a lower point than the normal 80 downward stroke of the plunger, to be engaged by the screw for causing the latter to compress the packing when the plunger is lowered beyond its normal lowermost limit and is rotated. 95

5. A pump comprising a casing, an open ended working barrel therein, a displacement plunger for the working barrel, like spacer rings at opposite ends of the working barrel with said rings having passages therethrough exterior to the working barrel, and a valve structure having means for securing it to either end of the working barrel in operative relation to either one of the spacer rings for controlling the passages there- 100 through. 105

6. A pump comprising a casing, a working barrel therein with exteriorly screwing threaded ends, a displacement plunger for the working barrel, like spacer rings on the 110 threaded ends of the working barrel with each spacer ring having passages therethrough, and a valve structure applied to one threaded end of the working barrel and adapted to either end and located in op- 115 erative relation to the passages through the spacer ring with which it is associated.

In testimony whereof I affix my signature in the presence of two witnesses.
